(57) **CLAIM**

The ornamental design for vented beverage can end, as shown and described.

DESCRIPTION

This application is also related by subject matter to co-pending application Ser. No. 29/385,513, filed Feb. 15, 2011 and Ser. No. 29/385,519, filed Feb. 15, 2011, each entitled "Vented Beverage Can End."

FIG. 1 is a top plan view of a vented beverage can end according to our design;

FIG. 2 is a side view thereof, the side view from opposing and orthogonal perspectives are identical to the view of FIG. 2; and,

FIG. 3 is a top perspective view thereof.

Other views of our design, including the bottom view are clearly understood from FIGS. 1-3. Any broken line portion of the drawings is included to show environmental subject matter only and forms no part of the claimed design.
